UNITED STATES PATENT OFFICE.

JOHN WARING WITSELL, OF CHARLESTON, SOUTH CAROLINA.

ADDING-MACHINE.

1,035,066.

Specification of Letters Patent. Patented Aug. 6, 1912.

Application filed June 20, 1911. Serial No. 634,241.

To all whom it may concern:

Be it known that I, JOHN WARING WITSELL, a citizen of the United States, and a resident of Charleston, in the county of Charleston, State of South Carolina, have invented a new and useful Improvement in Adding-Machines, of which the following is a specification.

My invention is an improvement in adding machines, and has for its object the provision of a simple and easily operated device of the character specified, of a size to permit it to be placed conveniently on the desk near the user, and which has few parts 15 to get out of order.

In the drawings—Figure 1 is a perspective view of the improvement; Fig. 2 is a transverse vertical section; Fig. 3 is a section on the line 3—3 of Fig. 2; Fig. 4 is a 20 perspective view of a driving pawl; Fig. 5 is a side view of a portion of the same; Fig. 5^a is a plan view of Fig. 5; Fig. 6 is a perspective view of the clearing device, and Fig. 7 is a perspective view of a modified 25 form of pawl arm.

The present embodiment of the invention comprises a casing 1 having a removable bottom plate 2 held in place by screws 3 and having a removable top plate 4 also held in place by screws 5. A shaft 6 is journaled 30 longitudinally of the case, and the upper front corner of the case is rounded on an arc of the circle, as indicated at 7, and is provided with a plurality of vertical spaced 35 parallel slots 8. A wheel is journaled on the shaft adjacent to each slot. Each wheel comprises a hub 10, and a perforated web 11, which is provided with a lateral annular flange 12 and 13 at each side co-axial 40 with the shaft. The flange 13 has a shorter radius than the flange 12, and is provided with a radial flange or rib 14 provided with spaced ratchet teeth 9 which extend through the adjacent slot into position for engagement by the finger to turn the wheel. The 45 flange 14 is connected to the web of the wheel at spaced intervals by transverse ribs 15, and each flange 12 is provided with a plurality of series of spaced numerals 16. The numerals run from 0 to 9 and are arranged 50 consecutively in each series. A shaft 17 is journaled in bearings 18 longitudinally of the case at the rear upper corner, and a plurality of pawl arms is jour-

naled on the shaft. Each arm comprises a 55 bar 19, having at one end a bearing 20 for engaging the shaft. The opposite end of the bar is enlarged and is rectangular in cross section, and is provided with a reduced transversely perforated lug 21. A pawl in 60 the shape of a link 22 is provided at one end with a lateral arm 23, and at the other with a journal pin 24 received in the perforation of the lug 21. The outer end of the journal pin is provided with a lug 25 extending 65 longitudinally of the body of the link and parallel therewith. At the side adjacent to the lug 25 the bar 19 is provided with a longitudinally extending lug 26, curving 70 slightly downward toward its free end for engaging the lug 25 to limit the downward swinging of the link. A rest 27 is arranged longitudinally of the case below the bars 19 and in position for engagement by the bars when in inoperative position. The rest 75 is faced with a layer 28 of felt or like material.

It will be noticed from an inspection of Fig. 3 that six wheels are provided, and that a pawl arm is provided for the first five 80 wheels, commencing at the left. The lateral arm 23 of the pawl engages the teeth, and a collar 29 is arranged between each pair of adjacent bearings 20 for spacing the arms. A sleeve 30 encircles the shaft 17 at 85 each end for holding the arms in proper position. It will be noticed that the portion 7 of the casing wall is grooved vertically at spaced intervals and that the slots 8 are in the bottoms of the grooves 31. The grooves form a guide for the finger, and the teeth 9 extend very slightly beyond the surface of the casing. The grooves, however, furnish ample space for the fingers. An opening 32 is provided at the side of the 90 upper end of each slot in register with the numerals, so that the numerals will appear successively through the openings as the wheels are turned, and each opening is preferably closed by a sheet of transparent material, as, for instance, glass. A series 95 of numerals is arranged between each pair of adjacent wheels, the said numerals running consecutively from above downward from 0 to 9. The pawls 22 are moving 100 pawls. The numerals 32 are for the purpose of indicating the numeral appearing at the opening.

In operation, the machine is first "cleared" by throwing in the clearing attachment, to be described, and afterward pressing downward on the points of the 5 wheels with the palm and fingers of the hand, until all the points are brought to a stop. The said attachment is so arranged, that when the wheels are brought to a stop, a row of naughts will appear beneath the 10 openings 13. The clearing attachment is now disconnected or thrown out of gear, by means of the crank, and the machine is then ready for the operation of addition. For instance, suppose that it is desired to add 15 the following:— $135 + 367 + 840$. To add the above sums, the forefinger of the right hand is placed on the uppermost point of the wheel at the right hand opening of the machine, the said wheel representing units, and the point is drawn down until it registers 20 with the numeral 5 in the series 32 of numerals adjacent to the said wheel. The finger is now engaged with the point of the wheel at its uppermost point and the wheel is again turned until this point registers with the numeral 7 in the series 32 of numerals. The numeral 2 will now appear in the first opening 31, from the right and the numeral 1 in the second opening from the right. The finger is now shifted to the 25 second or tens wheel and the said wheel is moved to bring the uppermost point into register with the numerals 3, 6 and 4 respectively of the series 32 of numerals at the left hand side of the said second wheel. When this has been done, the numeral 4 30 will appear in the opening above the said wheel, and the numeral 1 will appear in the third opening from the right of the machine. The third wheel from the right is now operated in the same manner to bring the uppermost tooth into register with the numerals 1, 2 and 8 respectively, after which it will be noticed that the numeral 2 appears 35 in the opening at the top of the third wheel and the numeral 1 in the opening at the top of the fourth wheel. The sum of the numbers given in the example is thus indicated as 1,242.

Each of the number wheels is provided with three series of numerals, each series running from naught to 9, and the series are separated by the transverse ribs 15, before mentioned. The transverse ribs 15 are 40 adapted to engage the lugs 26 of the pawl arms, to operate the said arms to cause the pawls to move the succeeding wheel. That is, when the unit wheel which is at the right of the machine, has been turned a distance 45 amounting to 9 teeth, the ribs 15 on the said wheel will engage the lug 26 of the adjacent pawl arm, and will cause the said pawl arm to swing upwardly as indicated in dotted lines in Fig. 2. The pawl 23 of the said 50 arm will engage the next wheel from the

right, that is, the tens wheel, and will move the said wheel the space of one tooth, thus indicating that the unit wheel has been turned a distance of ten teeth. When the tens wheel has been turned a distance corresponding to ten teeth, the hundreds wheel 70 will be moved, and in like manner the remaining wheels.

It will be understood that as many wheels may be provided as desired. In the present 75 instance, six are shown, this being enough for purposes of illustration. The clearing attachment shown more particularly in Fig. 6 consists of a shaft 35 journaled in the casing, and extending outside of the casing at 80 the right hand end, the said shaft being provided with lateral arms 37, corresponding in number and position to the number and position of the wheels, and designed to engage the ribs 15 of the wheels, to stop the 85 said wheels with a naught appearing at the opening 31 corresponding to the said wheel. The arms are thrown into and out of position for engaging the ribs by means of the crank arm 36. When the shaft is turned to 90 bring the arms into position for engagement by the ribs, and the wheels are turned, it will be evident that each wheel will be stopped with a naught appearing through the opening 31 corresponding thereto. 95

A holding pawl 33 is provided for each wheel, each pawl being secured to the casing by a screw 34 at one end, and engaging the teeth of the wheel at the other end. Each of the wheels is provided with a thin, flat, 100 long spring 39, having one end secured to the casing at 40, while the other end is provided with a slight angular portion 41, engaging spaced transverse notches 42 in the wheel. The engagement is very light, but 105 sufficient to impart a slight shock to the fingers when operating the wheel in the manner just described. The said springs 39 are designed to notify the operator when the wheel is in proper position, and the 110 grooves 42 are arranged between the designations of the numerals on the wheels. The springs will cause a slight stoppage distinctly perceptible however, warning the operator that the wheel is in such position that 115 a numeral appears through the opening 31 belonging thereto. The springs are not of sufficient strength to impede the movement of the wheels, but merely fix definitely the proper point at which the wheel should be 120 stopped.

In Fig. 5 is shown a modified form of pawl arm. The arm 45 is provided at its upper end with spaced bearings 46 for receiving the shaft 17, and a light spiral 125 spring 47 is arranged between the bearings on the shaft. One end of the spring bears against the arm, and the other end against the case. The lower end of the arm 45 is also provided with spaced bearings 48, and 130

a light spring 49 encircles the journal pin 24 of the pawl between the bearings, the said pin being journaled in the bearings. The object of the springs is to insure the 5 quick return of the pawl arms and pawls.

I claim:—

1. In an adding machine, a wheel comprising a disk provided at its periphery with oppositely extending annular flanges, 10 one of the flanges being of shorter radius than the other, and having an outwardly extending rib at its outer edge provided with teeth or points for engagement by the finger of the operator to move the wheel, a 15 plurality of series of consecutively arranged numerals on the other flange, transverse stops on the first-named flange between the disk and the rib between the series of numerals, a swinging pawl arm adjacent to 20 each wheel, each arm having means for engagement by the stops or ribs of the wheel to move the same, and having means for en-

gaging the teeth of the succeeding wheel to move the said wheel.

2. An adding machine, comprising a plurality of coaxial wheels, each having a plurality of series of consecutively arranged numerals on its periphery, and stops or ribs 25 between the adjacent series, each wheel having an annular series of teeth or points for engagement by the finger of the operator to move the said wheel, means adjacent to each wheel for engagement by the wheel to move the succeeding wheel, and means for alining the wheels, said means comprising, a shaft 30 journaled substantially parallel with the axis of the wheels, and having a lateral arm 35 for each wheel to engage the stops, and means for swinging the said shaft into and out of engaging position.

JOHN WARING WITSELL.
